ELECTRIC CONTROL FOR TIMER

George J. Dekan, Glen Ellyn, Ill., assignor of one-half to Ward Miller, Glen Ellyn, Ill.

Filed June 25, 1957, Ser. No. 667,857

14 Claims. (Cl. 324—70)

This invention relates generally to control systems for timers, and more specifically to an improved control arrangement for an electric timer of the type used in timing athletic runs such as those in track and field events.

Because of the substantial errors that generally result when a person attempts to directly operate a timer for some athletic event, many attempts have been made to produce control arrangements for the timers which will remove the human element thereby providing for more accuracy in timing. These timers are often electrically operated, and in the present state of the art, are highly efficient and accurate. To further state the problem that arises in the use of these timers, it is necessary to start the timer at the exact instant that the athletic event begins, and, while recording elapsed time, to stop the timer at the exact instant or instants when some portion or portions of the athletic event are completed. Arrangements presently known in the art solve this problem in many different ways, however, the common disadvantages of these arrangements are their high cost, complexity requiring trained personnel, and lack of versatility.

The object of the present invention is to provide a control arrangement for a timer overcoming each of the above noted disadvantages.

Another object of the present invention is to provide a highly versatile control arrangement for an electric timer for timing athletic events.

Another object of the present invention is to provide in an arrangement as noted above certain means for automatically signaling the start of a race and accurately timing only the starting portion of the race.

A further object of the present invention is to provide means in a construction such as that of the preceding paragraph whereby the athlete is prevented from anticipating the starting signal.

A further object of the present invention is to provide a construction such as that described in the preceding paragraphs with means whereby an athlete may himself initiate the operation of the invention to provide a starting signal, start the timer, and stop the timer after any elapsed portion of his run.

In addition to the previous objects, it is further the object of this invention to provide means with constructions such as described above for permitting the starting of the timer with the operation of a starting gun.

Other objects and the features of the present invention will be apparent upon a perusal of the following specification and drawing:

Figure 1 shows a use of the present invention by a runner to initiate the operation of the invention, to provide himself with a starting signal, with the invention automatically timing the first portion or starting portion of his race; and Figure 2 is a circuit diagram of the present invention.

The present embodiment is the preferred embodiment, but it is to be understood that changes can be made in the present embodiment by one skilled in the art without

departing from the spirit and scope of the present invention.

To generally describe the present invention, the various elements shown in Figure 2 are mounted in any suitable cabinet. A power source 10, which may be a 110-volt power line, or some other suitable power pack, provides power for operation of the instant invention. The timer 20 is an electrical timer having a suitable dial registering elapsed time, and comprises a continuously running motor, and a clutch arrangement which when engaged or operated causes the motor to operate the dial of the timer. A number of signal lamps 15 and 25 are included to indicate the proper operation of the invention. Various elements of the invention may be remotely located from the main cabinet. In other words, any of the signal lamps 15 and 25 may be remotely positioned, the timer dial of timer 20 may be remotely located, the various operating switches may be mounted either on the cabinet or at some remote location, and various ones of the switches may be provided in duplicate with parallel connections with some of the switches being located on the cabinet and with others being located at some remote position.

Turning next to a detailed description of the present invention, reference is first made to Figure 2. The ground side of the power source 10 is connected to conductor 11. The other side of the power source 10 is connected to one side of an on-off switch 13 through conductor 12. The other side of the switch 13 is connected to conductor 14. Signal lamp 15 is connected between conductor 11 and conductor 14. Conductor 14 is also connected in parallel to conductors 16 and 17. Conductor 17 is connected in parallel to conductor 18 and one side of the motor connection for the timer 20. Conductor 11 is connected to conductor 31, and the other side of the motor connection for the timer 20 is connected to conductor 31 through conductors 21 and 40. Conductor 18 is connected to one side of the primary of a step-down transformer 19, and the other side of the primary of the transformer 19 is connected to conductor 40. The secondary of the transformer 19 is connected to conductors 24 and 26. The signal lamp 25 is connected between conductor 26 and ground. Conductor 26 is connected to one side of each of a pair of ganged switches 41 and 42. Conductor 24 is connected to one side of each of a pair of switches 23 and 43. The other side of each of the switches 23 and 43 are connected to ground through conductor 22.

Three relays 34, 44 and 29 are used in the present embodiment. One side of the coil of relay 34 is connected to ground through conductor 45. The other side of the coil of relay 34 is connected to conductor 36. Conductor 36 is connected to one side of a switch 32. One side of the relay contacts 39 of armature 33 of relay 34 is connected to conductor 36. The armature 33 of relay 34 is connected to conductor 35 which in turn is connected to the other side of the switch 32. In addition to relay contacts 39 which are normally open, relay 34 is further provided with armature 38 and a set of normally open contacts 37. One side of the relay contacts 37 is connected to conductor 16. The armature 38 of relay 34 is connected through conductor 46 to one side of a rectifier 47 which may be of any suitable selenium or copper oxide type rectifying the alternating current of the power source 10 to a pulsating direct current. The other side of the rectifier 47 is connected to a resistor 48 and the other side of the resistor 48 is connected to one end of the resistance of a potentiometer 49. The movable arm of the potentiometer 49 is also connected to the junction of resistance 48 and resistance of the potentiometer 49. The other side of the resistance of the potentiometer 49 is connected to conductor 50. Conductor 50 is connected to one side of a condenser 51, to one side of the coil of relay 44 through conductor 52, and to armature

53 of relay 29. The other side of the condenser 51 is connected to conductor 31. Condenser 51 in cooperation with rectifier 47, resistor 48 and potentiometer 49 forms a time delay circuit, the operation of which will be described below.

The other side of the coil of relay 44 is connected to conductor 31 through conductor 54. Relay 44 comprises two sets of normally open contacts 55 and 56 respectively associated with armatures 57 and 58. The armatures 57 and 58 are both connected to conductor 59, which in turn is connected to conductor 27. Conductor 27 is connected between conductor 26 and armature 28 of relay 29. The contact of relay contacts 55 opposite form the armature 57 is connected to conductor 60. Conductor 60 is connected to the other side of the switch 42 opposite from that previously noted as connected to conductor 26. The contact of the relay contacts 56 opposite from armature 58 is connected to conductor 61. Conductor 61 is connected to conductor 62. One end of conductor 62 is connected to conductor 63, and the other end of conductor 62 is connected to one of the contacts of relay contacts 64 of relay 29.

Relay 29 comprises two armatures 28 and 53, with armature 28 associated with normally closed contacts 30 and normally open contacts 64, and with armature 53 associated with normally open contacts 65. One side of the coil of relay 29 is connected to conductor 62 and the other side of the coil is connected to ground through conductor 66. The contact of normally closed contacts 30 opposite from the armature 28 is connected to conductor 35. The armature 28 has previously been noted as connected to conductor 27. The contact of normally open contacts 65 opposite from armature 53 is connected to one end of a resistor 67 and the other end of resistor 67 is connected to conductor 31. The armature 53 of relay 29 was previously noted as connected to conductor 50. Conductor 63 to which conductor 62 was previously noted as connected, is connected at one end thereof to one side of the clutch of the timer 20. The other side of the clutch of the timer 20 is connected to ground through conductor 69. The other end of conductor 63 is connected to the other side of switch 41 opposite from that previously noted as connected to conductor 26.

The bell or sounder 70 may be of any suitable type known in the art, and one side thereof is connected to conductor 60 through conductor 71. The other side of the sounder 70 is connected to ground through conductor 72.

An additional switch 73 is connected across switch 41 by means of conductors 74 and 75.

Turning next to a detailed description of the various operations of the instant invention reference is again made to the drawing. Initially switch 13 is closed. Lamp 15 is then illuminated over an obvious circuit. The following circuit for the energization of the motor of the timer 20 is also completed: from conductor 11, power source 10, conductor 12, switch 13, conductor 14, conductor 17, the motor of timer 20, conductor 21, conductor 40, and conductor 31 to conductor 11. Thus the motor of the timer 20 will begin to operate. No operation of the timing dial will take place until the clutch of the timer 20 is energized. The primary of the transformer 19 which is connected parallel with the motor of the timer 20 is also energized at this time. At this point let it be assumed that switch 23, the Line Stop switch, is closed. The following circuit is then complete for lamp 25: from ground, through lamp 25, conductor 26, the secondary of transformer 19, conductor 24, switch 23, conductor 22 to ground. Thus lamp 25 will be illuminated.

If the Automatic Start or Get Set switch 32 is then closed, the following circuit for the energization of relay 34 is completed; from ground, conductor 45, the coil of relay 34, conductor 36, switch 32, conductor 35, contacts 30 of relay 29, armature 28 of relay 29, con-

ductor 27, conductor 26, the secondary of transformer 19, conductor 24, switch 23, conductor 22 to ground. The switch 32 need only be momentarily closed since upon the energization of relay 34, contacts 37 and 39 will be closed, and the closing of contacts 39 will complete a shunt circuit about switch 32 to lock up the relay 34. This shunt circuit extends from the coil of relay 34, through contacts 39, armature 33 of relay 34, and conductor 35 to contacts 30 of relay 29. The closing of contacts 37 of relay 34 completes the following circuit for the energization of relay 44: from the coil of relay 44, conductor 52, conductor 50, through the time delay circuit comprising condenser 51, potentiometer 49, resistor 48, rectifier 47, and then through conductor 46, armature 38 and contacts 37 of relay 34, conductor 16, conductor 14, switch 13, conductor 12, power source 10, conductor 11, conductor 31, conductor 54 to the coil of relay 44. By varying the amount of the resistance of the potentiometer 49 which is shunted by its movable arm, the time necessary to charge condenser 51 sufficiently to provide a suitable operating voltage across the coil of relay 44 may be varied. When a sufficient voltage is developed across the coil of relay 44, relay 44 will operate to close its contacts 55 and 56.

The closing of contacts 55 completes the following circuit for the energization of the bell or sounder 70: from ground, conductor 72, sounder 70, conductor 71, conductor 60, contacts 55 and armature 57 of relay 44, conductor 59, conductor 27, conductor 26, secondary of transformer 19, conductor 24, switch 23, conductor 22 to ground.

The closing of contacts 56 of relay 44 completes the following circuit for the operation of the clutch of the timer 20: from ground, conductor 69, the clutch of the timer 20, conductor 63, conductor 62, conductor 61, contacts 56 and armature 58 of relay 44, conductor 59, conductor 27, conductor 26, the secondary of the transformer 19, conductor 24, switch 23, conductor 22 to ground. Thus it may be seen that with the operation of relay 44, the sounder 70 is operated simultaneously with the operation of the clutch of the timer 20, and the timer will begin to record lapsed time on its dial.

The closing of contacts 56 also completes the following circuit for the energization of relay 29: from ground, conductor 66, the coil of relay 29, conductor 62, conductor 61, contacts 56 and armature 58 of relay 44, conductor 59, conductor 27, conductor 26, secondary of transformer 19, conductor 24, switch 23, conductor 22 to ground. Relay 29 will then operate closing contacts 64 and 65 and opening contacts 30. The opening of contacts 30 will break the previously described locking circuit for relay 34 and relay 34 will then restore, opening its contacts 37 and 39. With contacts 37 open, the previously described circuit for the energization of relay 44 is opened.

The closing of contacts 65 completes the following circuit thereby shunting the coil of relay 44; conductor 52, conductor 50, armature 53 and contacts 65 of relay 29, resistor 67, conductor 31, conductor 54 to the coil of relay 44. Because of the charge on condenser 51, relay 44 will not immediately restore to open its contacts 55 and 56. The time necessary for the restoring of relay 44 to open contacts 55 and 56 will be dependent upon the resistance of the coil 44, the resistance value of resistor 67 and the charge on condenser 51. When relay 44 does restore after a short period of time to open contacts 55 and 56, the opening of contacts 55 will break the previously described circuit for the operation of the sounder 70 and the sounder 70 will cease operation. Although contacts 56 of relay 44 previously completed the circuit for the operation of the clutch of the timer 20, the closing of contacts 64 of relay 29 completes the following alternate circuit to hold the clutch of the timer 20 operated: from ground, conductor 69, the clutch of timer 20, conductor 63, conductor 62, contacts 64 and

armature 28 of relay 29, conductor 27, conductor 26, secondary of transformer 19, conductor 24, switch 23, conductor 22 to ground. The closing of contacts 64 also completes the following circuit for maintaining relay 29 operated: from ground, conductor 66, the coil of relay 29, conductor 62, contacts 64 and armature 28 of relay 29, conductor 27, conductor 26, the secondary of transformer 19, conductor 24, switch 23, conductor 22 to ground. Thus it may be seen that at this point relays 34 and 44 are restored, the sounder 70 is not operated, and the timer 20 continues to operate to record the elapsed time.

To stop the timer 20 from recording elapsed time, it is merely necessary to open switch 23. The opening of switch 23 will break the previously described circuits holding the clutch of the timer 20 and the relay 29 operated. Relay 29 will restore opening its contacts 64 and 65 and closing contacts 30, and the timer 20 will cease recording elapsed time. The lamp 25 will also be extinguished.

The previously described operations may be easily applied to situations such as shown in Figure 1. If the Automatic Start or Get Set switch 32 is remotely located as a push button assembly 76 at the starting blocks of a runner, and if the line stop switch 23 is closed and has a flexible line 77 extending therefrom to the body of the runner, the runner may then upon his own initiative close switch 13 to initially energize the subject invention and set the movable arm of the potentiometer 49 at some suitable position. The position of the movable arm 49 may be graduated in seconds or fractions thereof or some entirely haphazard means may be used for setting the potentiometer 49. The runner would then place himself at the starting blocks and when preliminarily prepared would momentarily operate push button assembly 76, thereby momentarily closing switch 32. Immediately thereafter the runner would get set in preparation of starting a run and after a time interval determined by the setting of potentiometer 49, the subject invention will automatically operate as previously described to operate the bell or sounder 70 for a short period of time and start the recording of elapsed time by operation of timer 20. The runner would then begin to run. When the line 77, connected from the runner to switch 23, was stretched out to its full length, the switch 23 would be opened by line 77 to stop the timer 20. With the line 77 connected between the runner and the switch 23 of a measured length, the timer will show the elapsed time from the initial operation of the sounder 70 to the time at which the runner reached the end of the measured length of line 77. This feature of the present invention is very important in that it permits the athlete to practice proper starting of a run over and over without the necessity for any control of the timing mechanism by any person other than the athlete himself by providing an accurate timing of the athlete's start. A number of other well known means which are runner operated may be used to open switch 23. With the various possible settings of the potentiometer 49, the time between the initial operation of switch 32 and the time at which the sounder 70 is operated may be varied to prevent the athlete from anticipating the operation of the sounder 70. Although the operation of the timer has been described as ceasing upon the opening of the Line Stop switch 23, the Stop switch 43 which may be mounted on the cabinet may be used in place of the Line Stop switch 23. If the Stop switch 43 is to be used, the Line Stop 23 is opened and the Stop switch 43 is initially closed. Upon the operation of the timer 20, the switch 43 may be opened at any time to stop the recording of elapsed time.

If it is desired to start a race with the firing of a gun rather than with the sounder 70 the Gun Start switch 73 is associated with the starting gun in any suitable manner known in the art whereby the Gun Start switch 73 will be closed upon the firing of the gun. When the

gun is fired, and switch 73 is closed, the following circuit for the energization of the clutch of the timer 20 is completed: from ground, conductor 69, clutch of the timer 20, conductor 63, conductor 74, switch 73, conductor 75, conductor 26, secondary of transformer 19, conductor 24, and either Line Stop switch 23 or Stop switch 43 to conductor 22 and ground. As previously described, the timer 20 is stopped by the opening of either Line Stop switch 23 or Stop switch 43, depending upon which one was initially closed.

A race may be additionally started by the momentary closing of the ganged switches 41 and 42. The closing of switch 41 completes the following circuit for the operation of the clutch of the timer 20: from ground, 15 conductor 69, the clutch of the timer 20, conductor 63, switch 41, conductor 26, the secondary of transformer 19, conductor 24, and either switch 23 or 43 to conductor 22 and ground. Simultaneously the closing of switch 42 completes the following circuit for the operation of 20 the sounder 70: from ground, conductor 72, sounder 70, conductor 71, conductor 60, switch 42, conductor 26, secondary of transformer 19, conductor 24, and either switch 23 or 43 to conductor 22 and ground. Thus it may be seen that simultaneously the sounder 70 is operated and the timer 20 begins to record elapsed time. As 25 previously described, the timer 20 is stopped by the opening of either switch 23 or 43 depending upon which one had been previously closed.

From the foregoing it is apparent that in addition to 30 the various possible operations described above, many others may be made dependent of the particular requirements of some race.

Having described the invention what is considered new and desired to be protected by Letters Patent, is:

35 1. A control arrangement for an electric timer comprising a source of power, electrically operated signaling means, relay means including a condenser for connecting said source of power to said electric timer and to said electrically operated signaling means, said relay means being formed to operate responsive to a momentary energization thereof, said condenser being connected in said relay means to delay the operation thereof for a certain time interval after the initial energization of said relay means, and second relay means operating responsive to the operation of said first relay means for disabling said electrically operated signaling means after a short period of time and for continuing the connection of said source of power to said electric timer.

2. In a control arrangement for an electrical timer, a 50 power source, electrically operated signaling means, second relay means operable to simultaneously connect said power source to said timer and to said signaling means for operation thereof, third relay means operable to restore said second relay means after a relatively short time interval so that said signaling means is restored and to complete a circuit maintaining said power source connected to said timer for continuing operation thereof, manually operable and restorable means operable to simultaneously connect said power source to said timer 55 and to said signaling means independent of said second relay means for initial operation thereof and to operate said third relay means to complete said circuit maintaining said power source connected to said timer for continuing operation thereof when said manually operable 60 and restorable means is restored so that only said signaling means is restored when said manually operable and restorable means is restored.

3. In a control arrangement for an electrical timer as claimed in claim 2, wherein said second and third relay 70 means and said manually operable and restorable means includes a switch operable to restore said third relay means and disconnect said power source from said timer.

4. In a control arrangement for an electrical timer as 75 claimed in claim 2, wherein said manually operable and restorable means includes a manually operable

switch operable to initially connect said power source to said timer and to operate said third relay means.

5. In a control arrangement for an electrical timer as claimed in claim 2, wherein said manually operable and restorable means comprises a pair of ganged manually operable switches, one of said switches being connected to initially connect said power source to said timer and to operate said third relay means responsive to an operation thereof, the other of said switches being formed to connect said power source to said signaling means responsive to an operation thereof.

6. In a control arrangement for an electrical timer as claimed in claim 2, wherein manually operable first relay means is provided for operating said second relay means a certain time interval after the initial operation of said first relay means.

7. In a control arrangement for an electrical timer as claimed in claim 4, wherein a gun switch is connected in shunt of said manually operable switch, said gun switch operable to momentarily complete said shunt responsive to the firing of a gun.

8. In a control arrangement for an electrical timer as claimed in claim 6, wherein said first relay means includes means for varying the length of said certain time interval.

9. In a control arrangement for an electrical timer, a power source, electrically operated signaling means, a first relay means, a second relay means, a third relay means, means for momentarily operating said first relay means, said first relay means operating to complete a circuit for the operation of said second relay means and completing a locking circuit for maintaining said first relay means operated, said second relay means operable to simultaneously initially connect said power source to said electrically operated signaling means and to said timer for operations thereof and to complete a circuit for the operation of said third relay means, said third relay means operable to open said locking circuit for said first relay means so that said first and second relay means and said signaling means restore and for simultaneously completing a circuit for maintaining said power source connected to said timer.

10. A control arrangement for an electric timer comprising a source of power, electrically operated signalling means, second relay means operable to connect said source of power to said electric timer and to said electrically operated signalling means to begin the operations thereof, first relay means for operating said second relay means, manually operable means for operating said first relay means, and a time delay circuit for delaying the operation of said second relay means a certain period of

time, said time delay circuit comprising a condenser connected to said second relay means to delay the operation thereof until said condenser is charged and a variable resistor connected to said condenser and said first relay means to charge said condenser responsive to the operation of said first relay means.

11. In a control arrangement as claimed in claim 10 wherein third relay means is provided operating responsive to the operation of said second relay means for disabling said electrically operated signalling means after a short interval of time and continuing the connection of said source of power to said electric timer.

12. In a control arrangement for an electric timer, a power source, electrically operated signalling means, 15 manually operable circuit means for connecting said power source to said timer and to said signalling means for simultaneous operation thereof, means operating responsive to the operation of said circuit means for restoring said signalling means after a certain interval of 20 time and continuing the connection of said power source to said timer, said circuit means including a line switch operable to disable said circuit means to disconnect said power source from said timer, said line switch comprising a line connectable at one end thereof to a runner and 25 at the other end thereof to a switch for operation of said switch by said runner by pulling on said line.

13. In a control arrangement for an electric timer as claimed in claim 12 wherein said manually operable circuit means includes a time delay circuit operating responsive to the initial operation of said circuit means for delaying for a certain period of time the connection of said power source to said timer and to said signalling means, said time delay circuit comprising a resistor and condenser connected to control the delay period of time 35 for operation of said circuit means dependent upon the charging time of said condenser.

14. In a control arrangement for an electrical timer as claimed in claim 13 wherein said resistor is formed to be adjustable so that the charging time of said condenser 40 may be varied.
